CLAIM

The ornamental design for a light fixture, as shown and described.

DESCRIPTION

FIG. 1 is a bottom perspective view of a light fixture in accordance with my design, illustrating an adjustable position;

FIG. 2 is a top plan view of the light fixture in accordance with my design, illustrating an adjustable position;

FIG. 3 is a bottom plan view of the light fixture in accordance with my design, illustrating an adjustable position;

FIG. 4 is a front elevation view of the light fixture in accordance with my design, illustrating an adjustable position;

FIG. 5 is a back elevation view of the light fixture in accordance with my design, illustrating an adjustable position;

FIG. 6 is a side elevation view of the light fixture in accordance with my design, illustrating an adjustable position; and,

FIG. 7 is an opposite side elevation view of the light fixture in accordance with my design, illustrating an adjustable position.

The broken lines showing environmental structure are for illustrative purposes only and form no part of the claimed design.
